CAN OPENER

James A. Murdock, Chicago, Ill., assignor to
 Vaughan Novelty Mfg. Co. Inc., Chicago, Ill., a
 corporation of Illinois

Application November 22, 1937, Serial No. 175,781

4 Claims. (Cl. 30—9)

This invention relates to can openers and has for its principal object to provide an improved can opener.

A further object of the invention is to provide an improved can opener in which the elements which engage and cut the can are automatically brought into cutting position by the operation in the normal cutting direction of the actuating member and are brought out of engagement with the can by reverse movement of the actuating member.

A further object of the invention is to provide an improved resilient mounting of can-engaging elements whereby cans of different shapes may be received by the opener without undue stress to any operating part of the opener.

A further object of the invention is to provide a can opener in which can-engaging elements may be moved to engage the bead of the can on opposite sides and positively grip and drive the can when the opener is operated.

Other objects, advantages and capabilities of the invention will appear from the following description of a preferred embodiment thereof, taken in conjunction with the accompanying drawings, in which:

Figure 1 is a side elevation of the can opener in its normal initial position;

Fig. 2 is an end elevational view of the can opener, the operating crank being turned from the position shown in Fig. 1 without, however, moving the cam to can-engaging position.

Fig. 3 is a fragmentary side elevation showing the parts in cutting relation;

Fig. 4 is an end view corresponding to Fig. 3, showing a can being cut;

Fig. 5 is a sectional view, on a larger scale, taken on the line 5—5 of Fig. 3, showing the elements in cutting relation;

Fig. 6 is an end view of the eccentric member;

Fig. 7 is a sectional detail view, showing the position of the cams in initial can-receiving position;

Fig. 8 is a similar view showing the cams in an intermediate position corresponding to relative movements of the cutting elements or to cutting position;

Fig. 9 is a similar view showing the cams in cutting position;

Fig. 10 is a fragmentary view showing modified can-engaging elements, and

Fig. 11 is a similar view showing further modified can-engaging elements.

Referring to the drawings, the reference number 10 designates a socket member which may

suitably be secured to the wall. The socket member is provided at each side with marginal groove formations 11 which converge downwardly slightly from the vertical, for the purpose of receiving a complementary base plate 12 which is integral with the frame 13 of the opener. The frame 13 extends outwardly from the base 12 so as to provide ample space for the manipulation of the actuating member, which is preferably a crank arm 14.

The crank arm 14 comprises a radial arm 15 on which is rotatably mounted a handle 16. At its opposite end the radial arm 15 is rigidly secured to a shaft 17 which is rotatably mounted in a bore 18 in a cylinder 19. The bore 18 is located eccentrically in the cylinder 19 so that the shaft 17 is provided with an eccentric mounting in which it may rotate. The cylinder 19 is provided with a projection 20 for a purpose hereinafter described.

The cylinder 19 is rotatably mounted in a cylindrical opening 21 in a boss 22 provided in the forward part of the frame 13. The opening 21 slopes downwardly from the right-hand side to the left-hand side of the device and the shaft 17 extends through the opening 18 so that this shaft points downwardly away from the crank 14.

The right-hand flat surface of the boss 22 is provided with an opening 23 in which is received with a pressed fit a stop pin 24. On this face of the boss 22 is mounted a stationary cam member 25 which is provided with an apex 26 at its uppermost point. Opposite the apex 26 the cam member 25 is provided with stops 27 located on opposite sides of the pin 24 so that the cam member 25 is held stationary at all times. The cam member 25 is provided with an opening 28 in alignment with the bore 21 so that the cylindrical member 19 may extend therewith, as best seen in Fig. 5.

A movable cam and stop member 29 is mounted on the outer side of the stationary cam 25. The member 29 is provided with an opening 30 adapted to receive the shaft 17 and it is provided with an opening 31 adapted to receive the projection 20 of the cylinder 19 so that the cam and stop member 29 always moves with the cylinder 19. The radial arm 15 is provided with an annular chamber around the shaft 17, in which chamber is located a helical spring 32 which is adapted to press against the movable cam and stop member 29. This spring permits a limited resilient action longitudinally of the axis of the shaft 17 with respect to the frame 13 which allows a limited separation between the inner face of the can 33 and 55

the face of the shoulder 47 on the lower traction member 43. The other end of the shaft 17 is provided with a washer 33 which extends beyond the periphery of the bore 21 and bears against the left-hand face of the boss 22.

5 Beyond the washer 33 the shaft 17 is threaded. A dual-purpose driving element 34, having a threaded opening, is mounted on the shaft 17. The cutter 35 which may suitably be of the disc type, is also threaded on the end of the shaft 17. The dual-purpose driving element 34 serves both as a driving element engaging the top side of the bead of the can and as a pinion for engaging and driving the toothed portion 46 of the lower traction member 43. The cutter 35 serves as a lock nut to maintain the parts in assembled relation against the compression of a spring 32 bearing on the member 29.

Beneath the boss 22 the frame 13 provides a 20 solid portion within which is formed a substantially rectangular opening 36, which opens to the left, as best seen in Fig. 5. The opening 36 is slightly elongated relative to a block 37 which is inserted freely into the opening 36 and is normally held against movement by a resilient member 38 of rubber or other suitable material. This 25 block is located in a threaded opening 39 which extends from the lower side of the frame upwardly into the opening 36. A screw 40 is threaded into the opening 39 below the block 38 so as to provide a means of regulating the pressure required to hold the block 37 against displacement. At the same time the resilient member 38 permits the block 37 to move somewhat 30 when subjected to unusual or excessive strains.

The block 37 is provided with a shouldered chamber 41 in which is received a shouldered shaft 42, upon the outer end of which is mounted a traction member 43. The shaft 42 is provided 40 with an axial recess which opens to the right and contains a compression spring 44 which bears against the frame 13 and normally forces the shaft 42 outwardly so that it bears against the shoulder of the shouldered chamber 41, and 45 presses the lower traction member 43 into its outermost position when the can opener is idle and until complete engagement with the bead of the can is effected. Suitable shims 45, preferably of hard material, are located on the inner 50 end of the opening 36 so that the spring 44 bears against them. These shims 45 are provided to accommodate manufacturing tolerances so that the clearance between the inner face of the cutter 35 and the lower traction member 43 may be set 55 accurately at the time of assembly of the can opener. It will readily be understood that the traction member 43 is able to move inwardly under the influence of exterior force, and when the can opener is operated the inner face of the 60 lower traction member 43 bears against the outer face of block 37. The traction member 43 consists of a pinion having beveled peripheral teeth 46 adapted to mesh with the teeth of the dual-purpose driving element 34 when the cylinder 19 is located so as to bring the shaft 17 at its 65 lowest position.

The traction member 43 is provided on its outer side with a can-engaging shoulder 47 which may be peripherally serrated so as to enable it more 70 firmly to grip the underside of the bead of a can.

The arm 15 of the crank 14 is of channel section and receives a sliding latch member 48 which extends longitudinally of the arm 15. The latch 75 member 48 is retained in position by means of a

pin 49 extending transversely of the arm 15 and passing through a slot 50 in the latch member. The latch member 48 is guided against lateral displacement by means of abutments 51 located inside the arm 15. The outer end of the latch 48 5 is reduced in width, as best seen in Fig. 5, and the reduced end is engaged by a compression spring 52 which abuts against shoulders on the latch member 48 and against the outer end of the arm 15. The inner end of the latch member 48 is 10 adapted to engage a stop 53 in the interior of the arm 15. The arm 15 is cut away adjacent its pivot, as indicated at 54, so as to allow the arm to clear the stationary cam 25 and the movable cam and stop member 29 as the crank is 15 rotated, and to provide clearance for the lateral resilient movement of the shaft 17 and its assembly. The cam 25 and movable cam and stop member 29 are in alignment with a projecting part 55 of the latch member 48.

The movable cam and stop member 29 is best seen in Figs. 7, 8 and 9. This movable cam and stop member is provided with a detent formation 56 which is adapted to engage the pin 24 during cutting and to hold the member 29 immovable 25 during the cutting operation. The movable cam and stop member is also provided with a cam rise portion 57, 58 being the low point and 59 being the high point of the cam rise. Fig. 7 shows the position of the cams and associated 30 parts when the opener is in the can-receiving position. The latch 48 is in the full-line position and the shaft 17 is at an elevated position with respect to the axis of the cylinder 19, corresponding to the cutter 35 being in its elevated can-receiving position.

When the crank is rotated in the clockwise direction, as viewed in Fig. 7, the latch 48 is carried around the apex 26 of the cam 25 and owing to the elevated position of the shaft 17 it does not engage this apex. Continued rotation of the crank brings the latch 48 into its dot-and-dash position so that it engages the cam portion 57 adjacent its low point 58. Continued rotation of the crank causes the member 29 to rotate in clockwise direction, as viewed in Fig. 7, through the position shown in Fig. 8 to the position shown in Fig. 9. During this movement of the movable member 29, the shaft 17 is moved downwardly so that the latch 48 rides on the upper portion 50 of the stationary cam member 25.

As the latch member 48 approaches the apex 26 of the cam 25, the latch is moved outwardly clear of the low point 58 of the cam rise portion 57, and then moves over this cam rise portion clicking into the dot-and-dash position shown in Fig. 9. When the latch 48 reaches the apex 26 of the cam 25, the detent formation 56 just engages the pin 24 so that further rotation of the movable cam member 29 is prevented during continued rotation of the crank in the clockwise direction.

During repeated rotations of the crank in the clockwise direction the latch member 48 clears the lower portions of the cam members 25 and 29, as viewed in Fig. 9, on account of the low position of the shaft 17. During these continued rotations, however, the latch member 48 rides up to the apex 26 of the cam member 25, and over the cam rise portion 57. Such continued rotation of the crank proceeds until the cover of the can is completely cut. When cutting is complete the crank is moved in counter-clockwise direction until the latch 48 attains its dot-and-dash position shown in Fig. 9. Continued counter-clock- 70 75 80 85 90 95 98 99

wise movement of the crank brings the latch and the movable cam member 29 through the position shown in Fig. 8 back to the position shown in Fig. 7, when the reverse movement is 5 terminated by the engagement of the projection 57 with the pin 24.

The frame 13 is provided immediately below the cutter 35 and the traction wheel 43 with a flange 60 against which the edge of the can rests 10 during cutting, as seen in Fig. 4.

The operation is as follows. The cutter 35 is brought to elevated position, as shown in Fig. 2, by rotating the crank in counter-clockwise direction. The can 61 is then applied against the flange 60 and the lower edge of the upper bead 15 of the can is brought into engagement with the shoulder 47 on the traction wheel 43. The crank is then turned in clockwise direction, with the result that the latch 48 engages the cam projection 57 of the movable cam and stop member 29 and the shaft 17 is moved downwardly, carrying 20 the cutter 35 into its downward position shown in Figs. 4 and 5.

In so moving downwardly the lower portion 25 of the cutter wheel 35 is carried through the top of the can immediately inside the upper bead, as best seen in Fig. 4. It will be noted that the cutter wheel 35 rotates at all times with the crank and, consequently, the can puncturing movement 30 of the cutter wheel 35 is a combined rotary and downward movement. The downward movement of the cutter 35 brings the teeth of the driving element 34 both into engagement with the teeth 46 of the lower traction wheel 43 and with 35 the top side of the bead of the can so that continued rotation of the crank in the clockwise direction positively causes the can to rotate in the clockwise direction, the cutter wheel 35 acting upon the can cover around its whole periphery 40 so as to sever same from the can. When cutting is complete, the can is grasped by the left hand and the crank turned in the counterclockwise direction until it is arrested by the attainment of the position shown in Fig. 7 which, as 45 has been previously pointed out, corresponds to the elevated position of the cutter wheel 35. The open can is now removed and the operation is complete. The resilient mounting of the cutter 50 35 provided by the spring 32, and the freedom of movement provided for the traction wheel 43, enables cans of different types and variable structure to be handled without applying undue stresses to any part of the opener.

In the modification of the invention shown in 55 Fig. 10, only that portion of the dual-purpose element 34 which engages the teeth 46 is provided with teeth, as indicated at 75, the remaining portion, designated 76, being smooth. This smooth cylindrical portion 76 forces the bead of 60 the can against the serrated shoulder 47 of the traction member 43 and the can is rotated by said shoulder.

In the embodiment of the invention shown in 65 Fig. 11, the teeth on the member 34 engage only the bead of the can. The shoulder 47 which provides the lower abutment for the can bead may be plain or smooth. This shoulder is formed on a wheel 43' mounted in the same manner as the traction member 43 previously described. In this 70 embodiment, however, the member 43' is not provided with teeth and is not driven except by the movement of the can.

Although the invention has been disclosed in connection with the specific details of preferred 75 embodiments thereof, it must be understood that

such details are not intended to be limitative of the invention except in so far as set forth in the accompanying claims.

I claim:

1. A can opener having a frame, a bearing member rotatably mounted in said frame, a crank having a shaft eccentrically mounted in said bearing member, complementary can cutting elements on said shaft and said frame, a cam member mounted on said frame, a stop member mounted on said bearing member adjacent said cam member, means on said frame member adapted to cooperate with the stop member to limit the rotary movement of the bearing member to locate the can cutting elements in operative and inoperative relation, a latch on the crank adapted to engage a projection on the stop member to effect displacement of the bearing member, said cam having an apical portion which is adapted to elevate the latch above the projection 15 when the bearing member is in cutting position and the crank is rotated in can cutting direction. 20

2. A can opener having a frame, a bearing member rotatably mounted in said frame, a crank having a shaft eccentrically mounted in 25 said bearing member, complementary can cutting elements on said shaft and said frame, a cam member mounted on said frame, a stop member mounted on said bearing member adjacent said cam member, means on said frame 30 member adapted to cooperate with the stop member to limit the rotary movement of the bearing member to locate the can cutting elements in operative and inoperative relation, a latch on the crank adapted to engage a projection on the 35 stop member to effect displacement of the bearing member, said cam having an elevated portion which registers with the projection when the bearing member is moved to cutting position whereby the latch is elevated on to the projection 40 when the crank is operated in cutting direction, said projection having a portion extending beyond the elevated portion of the cam whereby the latch can engage the projection and carry the stop member past the cam to can releasing 45 position.

3. A can opener having a frame, a bearing member rotatably mounted in said frame, a crank having a shaft eccentrically mounted in 50 said bearing member, complementary can cutting elements on said shaft and said frame, a cam member mounted on said frame and having an apical portion, a stop member mounted on said bearing member adjacent said cam member, means on said frame member adapted to cooperate with the stop member to limit the rotary movement of the bearing member to locate the can cutting elements in operative and inoperative relation, a latch on the crank adapted to engage a projection on the stop member to effect 55 displacement of the bearing member, said projection having a cam formation, one end of which is within and the other end of which is beyond the apical portion of the cam, said stop means being located so that the first said end is brought into 60 register with the apical portion of the cam when the bearing member is in cutting position, whereby the latch is elevated on to the cam formation when the crank is operated in cutting direction, and the latch engages the projection and carries 65 it past the apical portion when the crank is rotated in the opposite direction.

4. A can opener having a frame, a bearing member rotatably mounted in said frame, a crank having a shaft eccentrically mounted in said 70 75

bearing member, complementary can cutting elements on said shaft and said frame, a stop member projecting from said frame at the end of the bearing member remote from the cutting elements, a cam member mounted on said bearing member held against rotation by said stop means, said cam member having an apical portion remote from said stop member, a second cam member mounted to move with said bearing member adjacent said cam member, means on said second cam member adapted to engage said stop means to limit the rotary movement of the bearing member to locate the can cutting elements in operative and non-operative relation, a latch on the crank adapted to engage the two cam mem-

bers, said second cam having a cam formation one end of which is within and the other end of which is beyond the apical portion of the first said cam, said stop member being located so that the first said end is brought into register with the apical portion of the cam when the bearing member is in cutting position, whereby the latch is elevated on the cam formation when the crank is operated in cutting direction, and the latch engages the cam formation and carries it past the apical portion when the crank is rotated in the opposite direction until the cutting elements are located in non-operative relation. 5 10 15

JAMES A. MURDOCK. 15
